ABSTRACT

An electronic timepiece which comprises a time standard that delivers a periodic signal of predetermined frequency, an electronic divider, an electromechanical converter controlled by the divider, time display means actuated by the converter, a two-phase voltage generator controlled by the time standard and a two-phase network supplied by the generator, the various stages of the divider being associated with one or the other of the network phases.

ELECTRONIC TIMEPIECE

DISCLOSURE

This invention relates to an electronic timepiece of the kind comprising a time standard delivering a periodic signal of predetermined frequency, an electronic divider for dividing said frequency, an electromagnetic converter controlled by the signal issuing from the divider, time display means driven by said converter and a DC voltage supply source, said divider including a series of elementary dividing stages of which at least some each comprise, firstly, an elementary amplifier formed by an insulated-gate field-effect transistor and by a capacitor in series with the transistor, said amplifier being supplied with a periodic voltage that provides the signal to be divided by the dividing stage under consideration and being controlled by a voltage source constituted by the input capacitance of said transistor, and secondly, a circuit for charging said capacitance and a circuit for periodically discharging said input capacitance, which is controlled by the output signal of said elementary amplifier, and said periodic voltage for supplying each intermediate dividing stage is taken from the point of connection of a pair of insulated-gate field-effect transistors that are connected in series with said source of DC supply voltage, the control voltage for one of said transistors being provided by the output signal of the amplifier and for the other of said transistors being provided by a periodic voltage having a frequency at least equal to that of said output signal but phase-shifted in relation thereto.

In U.S. Pat. Spec. No. 3,383,570 there is described an electronic timepiece which partly corresponds to that set forth above, in particular as regards the portion thereof which is intended to divide medium frequency signals and which is made up of a series of dividing stages, referred to as being of the "B" type in the above patent specification, in which the input capacitance of the transistor of the respective amplifiers, that provides the memory of the stage, is charged by the signal which is to be divided by this stage.

In this kind of circuit, the time for charging and discharging the memory-acting capacitance is directly dependent on the characteristics of the transistors used, in particular on their threshold voltage and on their slope. But because this charging time is relatively long the use of B-type circuits is limited to the division of medium frequency signals.

However, because of the particularly simple structure of these circuits, which greatly facilitates the manufacture thereof in integrated form, applicant has sought to use this same type of circuit to divide signals of particularly high frequency.

According to the invention, there is provided an electronic timepiece of the kind set forth which further comprises a two-phase voltage generator controlled by the time standard and adapted to produce a two-phase signal having a frequency equal to the frequency of the signal delivered by the time standard or to a multiple or submultiple of said frequency, and a two-phase network supplied by said generator, and wherein the second transistor of each of said pairs of transistors is connected, by its gate, to one or other phase of said two-phase network, in alternation from one stage to the next, and the gate of the transistor belonging to the elementary amplifier of each intermediate dividing stage is connected to the connecting point between the pair of transistors that control the supply of the amplifier of the next stage, said pair of transistors thus forming said charging circuit for the input capacitance of the transistor belonging to the amplifier of the dividing stage under consideration.

The accompanying drawings illustrate, by way of example and very diagrammatically, one form of embodiment of the electronic timepiece provided by the present invention:

FIG. 1 is a block diagram thereof;

FIG. 2 is a partial representation of its electronic circuitry; and

FIG. 3 is an explanatory diagram.

As shown in FIG. 1, the illustrated timepiece comprises a quartz oscillator O which delivers a periodic signal V_0 having a high frequency, say 2.4 m.c.p.s. to a generator G which serves to transform this signal into another, two-phase signal V_{ox} - V_{ov} of the same frequency, or, by way of variant, having a frequency corresponding to a multiple or to a submultiple of the oscillator frequency. This two-phase signal V_{ox} - V_{ov} is fed by a network X-Y to a divider DM which consists of a series of dividing stages whose supply is alternately controlled by one and then the other of the X and Y phases of this network, as will be described further on, and which serves to lower the frequency of the two-phase signal V_{ox} - V_{ov} issuing from the generator G to a value of 1 c.p.s. (low-frequency signal V_c).

This signal V_c serves to control a time-indicating device IT comprising an electromechanical converter CE and a gear train having three movable parts s, m and h, which are subjected to the action of the converter and which respectively drive the seconds, minutes and hour hands (not shown) of the timepiece.

FIG. 2 illustrates the features of the generator G, of the first three stages of the divider D and of the supply means of each of these stages whereas the oscillator O is only illustrated by a rectangle. Suffice it to say that this oscillator is here required to produce a periodic signal of particularly stable frequency with a very low power consumption.

The generator G consists of a cascade amplifier comprising two series-connected insulated-gate field-effect transistors T_{g1} and T_{g2} , a transformer T, e.g., a ferrite core transformer, and a voltage divider having resistors R_1 and R_2 connected in series with a voltage source P. The voltage divider serves to control transistor T_{g2} whereas transistor T_{g1} is controlled by the periodic signal delivered by the oscillator O. The winding of transformer T is connected at its middle point to the negative terminal of source P, its ends being each connected to one of the two phases of the X-Y network.

As is known, an amplifier of this kind produces at each end of the winding of transformer T an AC, sinusoidal, voltage V_{ox} or V_{ov} , having a phase difference of 180° from end to end (FIG. 3), so that the X-Y network effectively constitutes a two-phase voltage network.

Whatever may be the construction of the amplifier that is used, the latter can be so sized that the frequency of the two-phase voltage which is generated may be equal either to the frequency of the periodic signal delivered by the oscillator O, or to a submultiple or a multiple of this frequency, the above choice being essentially dependent on the kind of oscillator used, i.e., whether it is of very high frequency, of medium frequency or of low frequency, and on the size that is required for the oscillator and for the transformer.

As described, the electronic divider with which the timepiece according to the invention is provided is made up of a series of dividing stages of which the first three, I, II and III, can be seen in FIG. 2 and whose supply voltage is taken, in each case, from the point of connection between two insulated-gate field-effect transistors that are series connected between the terminals of source P and which are controlled in a manner described below.

In particular, stage I is supplied from the connecting point of two transistors T_{a1} and T_{b1} , the gate of the first being connected to the intermediate point of a capacitive voltage divider comprising capacitors C_a and C_b series connected between the positive terminal of source P and the X phase of the two-phase X-Y network, and the gate of the second, T_{b1} , being connected to the other, Y, phase of this network. D_a is a clamping diode serving to define the potential applied to the gate of transistor T_{a1} .

Stage II is supplied from the connecting point between two transistors T_{a2} and T_{b2} , the gate of the first being connected to the output of the preceding dividing stage (I) and the gate of the second (T_{b2}) being connected to the X phase of the two-phase network.

Stage III is supplied from the connecting point between two transistors T_{a3} and T_{b3} , the gate of the first being connected to

the output of stage II and the gate of the second (Tb_3) being connected to the Y phase of the two-phase network.

As a general rule, each stage starting from the second of the electronic divider provided in the timepiece according to the invention is supplied by the source P through the intermediary of a pair of insulated-gate field-effect transistors Ta_n and Tb_n , the gate of the first (Ta_n) being controlled by the periodic signal issuing from the preceding dividing stage ($n-1$) and the gate of the second transistor (Tb_n) being connected to one or the other of the X and Y phases of the two-phase X-Y network, in alternation from one stage to the next.

The structure of the first stage (I) of the divider is slightly different from that of the following stages. It has two elementary amplifiers each comprising an insulated-gate field-effect transistor, T_{11} and T_{14} respectively, and a capacitor, C_{11} and C_{13} respectively, series connected with the transistor, which two amplifiers are supplied in parallel with a periodic signal taken from an intermediate point of the circuit located between the two transistors Ta_1 and Tb_1 .

The elementary amplifier consisting of the transistor T_{14} and of the capacitor C_{13} is controlled by a voltage source provided by the input capacitance of transistor T_{14} , indicated in broken lines and identified by reference C_{p1} , which capacitance is charged from a point located between transistors Ta_2 and Tb_2 and through a capacitor C_{14} , and is periodically discharged by a circuit that comprises two insulated-gate field-effect transistors T_{12} and T_{13} . The transistor T_{12} is controlled by the output signal of the amplifier formed by transistor T_{11} and capacitor C_{11} , through a transistor T_{15} whose gate is connected to the Y phase of the X-Y network via a capacitor C_{15} . Transistor T_{13} is connected, by its gate, to the X phase of the X-Y network via a capacitor C_{12} .

The elementary amplifier formed by transistor T_{11} and by C_{11} is controlled by the output signal of the elementary amplifier formed by transistor T_{14} and capacitor C_{13} . This same output signal is also used to control transistor Ta_2 .

Clamping diodes D_{a11} and D_{12} determine the potential of the gates of transistors T_{15} and T_{13} , respectively.

The subsequent dividing stages are of identical structure. Each comprises two elementary amplifiers of the previously mentioned kind, which for instance, in the case of stage II, are formed by a transistor T_{24} or T_{21} , respectively, and by a capacitor C_{23} or C_{21} respectively, arranged in series and supplied with a signal taken from the point of connection between transistors Ta_2 and Tb_2 .

The control voltage source for amplifier $T_{24}-T_{23}$ is formed by the input capacitance C_{p2} of transistor T_{24} , which capacitance is charged through a capacitor C_{24} from the point of connection between the transistors Ta_3 and Tb_3 for controlling the supply of the next stage (III).

Capacitance C_{p2} is periodically discharged by means of a circuit comprising two insulated-gate field-effect transistors T_{22} and T_{23} of which the first is controlled by the output signal of amplifier $T_{21}-C_{21}$ and the second is controlled by the Y phase of the X-Y network via a capacitor C_{22} . The potential at the gate of transistor T_{23} is determined by a diode D_{22} .

The elementary amplifier $T_{21}-C_{21}$ is controlled by the output signal of amplifier $T_{24}-C_{23}$, i.e., by the output signal of stage III. This same signal is used to control transistor Ta_3 .

As described, transistors Tb_1 , Tb_2 , Tb_3 , Tb_4 , . . . etc., which help to control the supply of dividing stages I, II, III, IV, etc., are connected by their gate to one or the other phase of the two-phase X-Y network, in alternation from one stage to the next.

Similarly, transistors T_{13} , T_{23} , T_{33} , . . . etc., which belong to the circuits for discharging capacitances C_{p1} , C_{p2} , C_{p3} , . . . etc. of stages I, II, III, . . . etc., are connected by their gate to one or the other phase of the two-phase X-Y network, in alternation from one stage to the next.

As a general rule, the X or Y phase by which the transistor Tn_3 of stage n is controlled is the same as that associated with the gate of transistor Tb_{n+1} .

All of the stages of the described divider, except the first, operate in the same manner and the operation of the second stage will now be given by way of example. To this end, an analysis will be made of the evolution of the potential at points a_1 , b_1 , d_2 , M , a_2 and b_2 of the circuit illustrated in FIG. 2 with reference to FIG. 3.

Let it first of all be assumed that the gate of transistor Ta_2 receives from Stage I periodic pulses (signal V_{a1} in FIG. 3) that are in phase with the alternating signal V_{ox} of the Y phase of the two-phase network whereby transistor Ta_2 is periodically opened at the frequency of signal V_{a1} . Let it furthermore be assumed that, at the start, the input capacitance C_{p2} of transistor T_{24} is discharged (signal $V_M=0$) so that this transistor is blocked.

When the first pulse of signal V_{a1} reaches transistor Ta_2 , the capacitance formed by the dividing stage II is discharged through this transistor so that the potential Vb_1 at point b_1 of this stage becomes zero.

Since transistor Tb_2 is controlled by signal V_{ox} , which is phaseshifted by 180° in relation to the signal V_{ov} , this transistor opens so that the capacitance of dividing Stage II is recharged (signal Vb_1) while transistor T_{24} is still blocked. This causes a potential Va_2 to appear at the gate of transistor Ta_2 , whereas transistor Tb_3 is blocked since it is controlled by the Y phase of the two-phase network: the capacitance of Stage II is thus discharged through transistor Ta_3 (see signal Vb_2 in FIG. 3).

During the subsequent half-period of the alternating signal V_{ov} , the capacitance of dividing Stage III is recharged since transistor Ta_3 is blocked, as will now be described.

Because the capacitance of stage II became discharged when the first pulse of signal V_{a1} reached transistor Ta_2 , the potential at point d_2 of this stage is zero and transistor T_{23} is blocked. It follows therefore that, at the instant when the capacitance of Stage III begins to be recharged, the input capacitance C_{p2} of transistor T_{24} also becomes recharged, via capacitor C_{24} (potential V_M in FIG. 3), despite the fact that the transistor T_{23} alternately opens and closes at the frequency of signal V_{ov} .

When the control voltage of transistor T_{24} reaches the threshold voltage level of the latter, the transistor opens thereby causing the input capacitances of transistors Ta_3 and T_{21} to become discharged and causing these transistors to become blocked (formation of the first pulse of signal Va_2).

The input capacitance C_{p2} of transistor T_{24} acts as a memory for Stage II as it is always charged when transistor Ta_2 receives the next pulse of the signal V_{a1} emanating from Stage I, i.e., when the capacitance of stage II is being discharged then to become recharged to form a new pulse of signal Vb_1 .

Because capacitance C_{p2} is charged transistor T_{24} is open and point a_2 thus remains at potential zero (suppression of a pulse of signal V_{a1}). It follows therefore that transistor T_{21} remains blocked and that potential Vd_2 at point d_2 of the circuit rises sufficiently to cause transistor T_{22} to open, whereas transistor T_{23} is blocked since the leading edge of signal Vd_2 is in phase with the alternating voltage V_{ox} whereas transistor T_{23} is controlled by the alternating voltage V_{ov} , which is phaseshifted by 180° in relation to the first. When transistor T_{23} , capacitance C_{p2} discharges through this transistor and through transistor T_{22} which is always open.

Stage II is now in the same state as when the first pulse of signal V_{a1} arrived so that the third pulse of this signal will cause a pulse of signal Va_2 to form whereas this will not be the case for the fourth pulse of V_{a1} , etc.

This kind of dividing stage cannot however be used as the first stage of the divider since the frequency of the signal appearing at its point b_1 would be equal to that of the voltage controlling the transistor T_{23} : if transistor T_{23} were open the potential at point d_2 would become zero and the memory-acting capacitance C_{p2} could not be recharged with the result that the dividing stage could supply no pulse at its output.

To overcome this drawback, the structure of the first dividing stage has been slightly modified by inserting a transistor

T_{15} in the control circuit of the insulated gate of transistor T_{12} , transistor T_{15} being controlled off the same Y phase of the X-Y network to which is connected the gate of transistor T_b , but through a capacitor C_{15} .

It follows therefore that when a voltage pulse appears at point d_1 of stage I, the input capacitance of transistor T_{12} becomes charged via transistor T_{15} . Since this capacitance remains charged, the memory-acting capacitance C_p of transistor T_{14} will become discharged when transistor T_{13} is opened by the voltage V_{ox} of phase X. The input capacitance of transistor T_{12} will be discharged via transistors T_{15} and T_{11} by the following pulse of the output signal V_{a1} of this stage I.

As is apparent from the above description, the charging of the memory-acting capacitance C_p of each dividing stage and its discharge are made to take place in a "forced" manner, so that their duration is no longer directly dependent on the characteristics of the transistors that are used, in particular on their threshold voltage and on their respective slope, as was the case with the B-type dividing stages described in U.S. Pat. Spec. No. 3,383,570.

This provides considerable latitude as regards the size of the transistors used in Stages I, II, III, etc.

Moreover, the dissipated power, which is already very much reduced by virtue of the operational principle of the described circuit, can be decreased still further by so choosing the inductivity of transformer T as to form a tuned circuit with the capacitance of the supply system of the various dividing stages, which capacitance is made up of the control capacitances of transistors T_{b1} , T_{b2} , T_{b3} , T_{b4} , ..., T_{b15} , T_{13} , T_{23} , T_{33} , ..., of the capacitance of the voltage divider C_a-C_b , and of that of all connections with the X and Y phases of the two-phase network. The energy that is periodically stored in the capacitance provided by the supply system is thus to a large extent recovered so that the power consumption in the succession of stages comprised by the described divider is very low.

It should moreover be pointed out that the described divider is particularly well suited to be made in integrated circuit form since it is made up exclusively of Mos transistors of one conductivity type and of Mos capacitors.

I claim:

1. An electronic timepiece comprising a time standard delivering a periodic signal of predetermined frequency, an electronic divider for dividing said frequency, an electromagnetic converter controlled by the signal issuing from the divider, time display means driven by said converter and a DC voltage supply source, said divider including a series of elementary dividing stages of which at least some each comprise, firstly, an elementary amplifier formed by an insulated-gate field-effect transistor and by a capacitor in series with the transistor, said amplifier being supplied with a periodic voltage that provides the signal to be divided by the dividing stage under consideration and being controlled by a voltage source

constituted by the input capacitance of said transistor, and secondly, a circuit for charging said capacitance and a circuit for periodically discharging said input capacitance, which is controlled by the output signal of said elementary amplifier

5 and said periodic voltage for supplying each intermediate dividing stage is taken from the point of connection of a pair of insulated-gate field-effect transistors that are connected in series with said source of DC supply voltage, the control voltage for one of said transistors being provided by the output signal of the amplifier and for the other of said transistors being provided by a periodic voltage having a frequency at least equal to that of said output signal but phase-shifted in relation thereto, said timepiece further comprising a two-phase voltage generator controlled by the time standard and 10 adapted to produce a two-phase signal having a frequency equal to the frequency of the signal delivered by the time standard or to a multiple or submultiple of said frequency, and a two-phase network supplied by said generator, and wherein the second transistor of each of said pairs of transistors is connected, by its gate, to one or other phase of said two-phase network, in alternation from one stage to the next, and the gate of the transistor belonging to the elementary amplifier of each intermediate dividing stage is connected to the connecting point between the pair of transistors that control the 15 supply of the amplifier of the next stage, said pair of transistors thus forming said charging circuit for the input capacitance of the transistor belonging to the amplifier of the dividing stage under consideration.

2. An electronic timepiece according to claim 1, wherein 30 the circuit for controlling the periodic discharge of the input capacitance of the transistor of the elementary amplifier of each intermediate dividing stage comprises, firstly, a second elementary amplifier consisting of an insulated-gate field-effect transistor and of a capacitor in series with the transistor, said amplifier being supplied with the signal to be divided by the dividing stage under consideration and being controlled by the output signal of this stage, and secondly, at least two insulated-gate field-effect transistors, in series, between the gate of the transistor of the first amplifier and earth, the first of said 35 two transistors being controlled by the output signal of the second amplifier and the second transistor being controlled by a signal having a frequency at least equal to that of the signal to be divided by the dividing stage, and wherein said second transistor is controlled by the phase of the two-phase network to which is connected the second transistor of the pair of transistors that control the supply of the next dividing stage.

3. An electronic timepiece according to claim 2, wherein 40 said generator comprises a transformer to which is connected said network, and wherein the inductivity of the transformer and the charging capacitance of the generator are so chosen as to form a tuned circuit on the frequency of the two-phase signal of the network.
